UNITED STATES PATENT OFFICE.

COLE STICKLE, OF INDIANAPOLIS, INDIANA.

STEAM-PRESSURE REGULATOR.

1,378,630.

Specification of Letters Patent. Patented May 17, 1921.

Application filed August 11, 1919. Serial No. 316,806.

To all whom it may concern:

Be it known that I, COLE STICKLE, a citizen of the United States, and a resident of Indianapolis, county of Marion, and State 5 of Indiana, have invented a certain new and useful Steam-Pressure Regulator; and I do hereby declare that the following is a full, clear, and exact description thereof, reference being had to the accompanying drawings, in which like numerals refer to like parts.

The object of this invention is to improve the operation of pressure reducing mechanisms employed in reducing the pressure of 15 steam and the like, and particularly so as to cause the operation thereof to be smooth and silent and free from any knocking or pounding noise.

This invention consists in combining with 20 the reducing valve mechanism, connected with high and low pressure pipes, of auxiliary means controlled by fluid under pressure independently of the main pipe, and means controlled by the low pressure steam 25 or fluid for controlling the pressure in said auxiliary means.

The full nature of the invention will be 30 understood from the accompanying drawings and the following specification and claim.

In the drawings Figure 1 is a side elevation of the mechanism with parts broken away. Fig. 2 is a central vertical section through the timer for controlling the fluid 35 in the auxiliary pipe. Fig. 3 is a side elevation of the reducing valve mechanism with parts in section. Fig. 4 is a central vertical section through the reducing valve and associated parts. Fig. 5 is an elevation of a 40 modified form of the apparatus. Fig. 6 is a vertical section through the portion shown at the upper left hand corner of Fig. 5.

There is shown herein a high pressure pipe 10 leading from any suitable source of 45 fluid under high pressure, connected with a low pressure pipe 11 by a reducing valve mechanism 12 which may be of the usual type. The valve stem 13 of the reducing valve extends upwardly and is mounted on 50 a frame 14 secured upon the reducing valve mechanism, and in said frame a lever 15 is fulcrumed at 16 between its ends, and at 17 is pivoted to the reducing valve stem 13, and at 18 is pivoted to a plunger rod 19. Therefore 55 the lever 15 is pivoted to said parts on the opposite side of the fulcrum, as herein

shown, although this particular manner of mounting is not necessary. A weight 20 is suspended from one end of the lever 15 and a weight 21 from the other end, which 60 weights it is understood are adjustable by adding weight thereto or taking weight therefrom.

The plunger rod 19, see Fig. 3, extends into a cylinder 22 and is secured to the piston 23, and said cylinder is in connection with an auxiliary pipe 25 which runs to a regulating valve chamber 26 that is connected with a pipe 27, through which fluid under pressure flows. This pipe 27 may be connected with a city water supply system or any other water supply system where water is supplied under regular pressure independently of the means for creating the pressure in the high pressure pipe 10. The 70 regulating valve 28 in the valve chamber 26 is operated by a valve stem 30 that extends in a diaphragm chamber 31 and is connected with the diaphragm 32 therein. A weight regulating lever 33 is fulcrumed at its end at 75 34 in the frame 35 which carries the diaphragm and said lever is pivoted at 36 to the valve stem 30 and carries the weight 37 on its outer end. A pipe 39 extends from the lower side of the diaphragm chamber 31 to 80 the low pressure pipe 11.

The reducing valve may be constructed as shown in Fig. 4 where the double valve 85 113 on the lower end of the rod 13 closes in the seat 114 as it moves downward and opens 90 as it moves upward. The weights 20 and 21 and the mounting of the lever 15 is such that they will normally hold the valve 113 open.

The operation is as follows: When the 95 pressure in the low pressure pipe 11 is too high, the fluid acting through the pipe 39, will lift the diaphragm 32 and open the valve 28 and admit fluid under pressure from the normal pressure pipe 27 to the pipe 25 and that will actuate the plunger 23 and 100 rod 18 and lever 15, which will move the reduction valve 12 toward closed position and thus reduce the pressure in the low pressure pipe 11. On the other hand if the pressure is at any time too low in the low 105 pressure pipe 11, the diaphragm will descend and close the valve 28 and shut off the passage of fluid under pressure through the auxiliary pipe 25 and the plunger 23 and permit the latter to descend and cause 110 corresponding movement of the lever 15 and reduction valve stem 13, which opens the

reduction valve a little more, thus increasing the pressure in the low pressure pipe.

In the modified apparatus, shown in Figs. 5 and 6, some of the parts are arranged to work oppositely to that shown in Figs. 1 to 4, but to accomplish the same result in substantially the same way. There, as seen in Fig. 6, the valve 28 is below the port 128 instead of above it as in Fig. 2, and the lever 33 and weight 37 tends to hold the valve open and permit the fluid under pressure in pipes 25 and 27 to pass through to the cylinder 22 and force the piston 23 upward and tend to hold the right hand end of the lever 15 upward and thus hold the reduction valve 113 upward and open. With this arrangement the maximum pressure of the water acts normally on the piston 23, while in the construction shown in Figs. 1 to 4 the minimum pressure of the water acts normally on said piston 23. Therefore, in this modified form, the reduction valve is caused to move to a closing position when the pressure of water in pipe 25 is diminished so as to allow the weighted end 21 of lever 15 to descend.

In order that the modified form may work as above explained, the fulcrum of lever 15 is changed to the opposite side of rod 13, from that shown in Fig. 3 to that shown in Fig. 5, where it is fulcrumed on the rocking bar 115 that is pivoted to the ear 116, see Figs. 3 and 5. Thus when weight 21 descends, the reduction valve is closed, while in Fig. 3 such movement of weight 21 causes the reduction valve to open. When the pressure becomes too high in the low pressure pipe 11 the diaphragm of the regulator is forced upward and the valve 28 tends to close and reduce the pressure in

the auxiliary pipe 25 so that it lets the piston 23 descend somewhat and cause the reduction valve to correspondingly move toward closing position. The low pressure in pipe 11 will cause the reversal of the parts just mentioned and thus tend to open the reduction valve.

Therefore, it is seen there is more than one way to arrange the mechanism to operate as desired, the chief feature of the means being the utilization of the pressure in the auxiliary pipe to control the reduction valve in the main pipe. With this mechanism the parts will operate automatically to regulate the reduction valve, and do so silently and without any knocking or disagreeable characteristics during the operation thereof.

The invention claimed is:

The combination with high and low pressure pipes, and reduction valve mechanism connecting them having an upwardly extending valve stem, of a frame rigidly mounted on said valve mechanism through which said valve stem reciprocates, a lever fulcrumed between its end in said frame, a weight on each end of said lever, means for pivoting the lever to the valve stem for controlling it, a plunger mounted on the frame, a plunger rod extending therefrom and reciprocable in the frame and pivoted to said lever for actuating it, an auxiliary pipe connected with said plunger for operating it by fluid under pressure therein independently of the high pressure pipe, and means controlled by the fluid under pressure in the low pressure pipe for regulating the pressure in said auxiliary pipe.

In witness whereof, I have hereunto affixed my signature.

COLE STICKLE.
